VEHICLE-FENDER.

1,083,824.

Specification of Letters Patent.

Patented Jan. 6, 1914.

Application filed June 10, 1913. Serial No. 772,772.

To all whom it may concern:

Be it known that I, DOMIZIO GHEZZI, a subject of the King of Italy, and a resident of the city of New York, borough of Manhattan, in the county and State of New York, have invented a new and Improved Vehicle-Fender, of which the following is a full, clear, and exact description.

Among the principal objects which the present invention has in view are: to provide an apparatus of the character named having a yielding buffer and grasping arms arranged to support a body from falling; to provide means whereon the body may rest or recline after being lifted from the ground; and to simplify and economize the construction.

One embodiment of the present invention is shown in the accompanying drawings, in which—

Figure 1 is a front elevation of a vehicle of the automobile type, having applied thereto a fender constructed and arranged in accordance with the present invention; Fig. 2 is a top plan view of the fender shown in Fig. 1, the supporting arms being shown in broken lines in partially-closed position; Fig. 3 is a detail view, on an enlarged scale, showing in vertical section the buffer-supporting arms and mounting therefor; and Fig. 4 is a detail view showing the trigger latch employed for holding the supporting arms in outspread position.

As seen in the accompanying drawings, the fender is mounted upon the automobile structure to extend forward of the wheels thereof, the means for supporting the same embodying primarily a relatively rigid bow-shaped frame 9. The ends of the frame 9 are advanced in a forward direction, and are there provided with collars 10 adapted to receive in holding relation a pneumatic tube 11 when the same is drawn taut between the collars 10. The pneumatic tube 11 is formed to a suitable size, and is provided in a conventional manner with means for inflating the same.

The tube 11 serves as a buffer, against which the body of the person may strike. The tube cushions the blow upon the body, to avoid imparting injury or hurt to the person struck thereby. Also, the resiliency or yield of the tube 11 is relatively universal in its entire length. About midway, the tube is provided with a rearwardly-extend-

ing arm 12, which is pivotally connected with a forked bell crank lever 13, said lever being mounted on a pivot pin 14 extending through bearings provided therefor in a bracket 15. When the tube 11 is struck and forced backward, the lever 13 is rocked on its pivot pin 14 to depress the rearward arm of said lever.

Pivotally connected with the arm of the lever 13 is a trigger latch 16. The latch 16 is yoke-shaped, having two upstanding arms 17 spread to be interposed in the path of supporting arms 18 to prevent the closure thereof. The arms 18 are pivotally mounted on a vertical shaft 19, which is extended from the top of the bracket 15, as shown best in Fig. 3 of the drawings.

Intermediate the bracket 15 and the arms 18 is a spiral spring 20 wound about the shaft 19 and forming a seat for the arms 18. The terminals 21 of the spring 20 extend upward behind the arms 18, and operate to close said arms upon each other forward of the vehicle and of the tube 11 mounted thereon.

From the foregoing, it will be seen that whenever a person is struck by the tube 11 of a fender constructed and arranged in accordance with the present invention, the trigger latch 16 is depressed to remove the arms 17 thereof from holding relation with the arms 18, which are then closed upon each other by the spring 20, each branch of the arm being at liberty to move independently of the other arm. In this manner, it will be seen that whether the body struck be centrally disposed with reference to the vehicle or the fender, the arms 18 will close upon the body to prevent the body from being knocked to the ground.

After the fender has been operated by striking the body, and the arms 18 have operated in the manner described, to reset the same is a simple operation, it being required only that the arms 18 shall be spread and forced backward behind the arms 17 of the latch 16. The forward pull of the tube 11 will, under all conditions, serve to maintain the latch in its lifted position, to hold the arms 18.

To form a hammock-like rest or pocket, a netting 22 is firmly attached to the frame 9 and to the tube 11. The method of securing the same to said frame and tube may vary. The simple means of wrapping said frame

and tube and sewing the wrapped portions of the netting has been adopted by me. The netting 22 is preferably arranged to form a slack portion to avoid restraining the action of the tube 11 when yielding to the weight of a body.

While the arms 18 will prevent the body falling to the earth, the netting 22 will serve as a seat to partially support the body, thereby preventing the dragging or trailing of the members of the body in contact with the ground.

In mounting the fender upon a vehicle, the tube 11 may be placed sufficiently low to catch and carry a child, while the arms 18 may be disposed so that, if the tube 11 be struck, they will grasp a person at the height of the hips, waist or shoulder.

While I have herein described with particularity the construction and arrangement of the elements of the fender, it will, nevertheless, be understood that the construction and arrangement may be varied to suit the desires or needs of the purchaser or manufacturer, and this without altering the scope of the present invention.

Claims—

1. A vehicle fender, comprising a supporting frame the ends whereof are curved forwardly to a point in advance of the wheels of a vehicle and the body thereof; a pneumatic tube stretched between the ends of said supporting frame; a plurality of curved arms pivotally mounted on said frame, said arms being curved to correspond with said supporting frame; a coil spring operatively engaging said arms to fold the same together; a latch mounted on said frame to fold said arms out of operation; and a lever operatively connecting said latch and said pneumatic tube to be operated by said tube to release said arms when the tube strikes a relatively stationary body.

2. A vehicle fender, comprising a supporting frame the ends whereof are curved forwardly to a point in advance of the wheels of a vehicle and the body thereof; a pneumatic tube stretched between the ends of said supporting frame; a plurality of curved arms pivotally mounted on said frame, said arms being curved to correspond with said supporting frame; a coil spring operatively engaging said arms to fold the same together; a latch mounted on said frame to fold said arms out of operation; a lever operatively connecting said latch and said pneumatic tube to be operated by said tube to release said arms when said tube strikes a relatively stationary body; and a supporting fabric structurally connected with said frame and said tube.

3. A vehicle fender, comprising a supporting frame the ends whereof are curved forwardly to a point in advance of the wheels of a vehicle and the body thereof; a pneumatic tube stretched between the ends of said supporting frame; a plurality of curved arms pivotally mounted on said frame, said arms being curved to correspond with said supporting frame; a coil spring operatively engaging said arms to fold the same together; a latch mounted on said frame to fold said arms out of operation; a lever operatively connecting said latch and said arms when said tube strikes a relatively stationary body; and a net operatively uniting said frame and said tube to form a support for a body when lifted from the ground by said tube.

In testimony whereof I have signed my name to this specification in the presence of two subscribing witnesses.

DOMIZIO GIIEZZI.
